UNITED STATES PATENT OFFICE.

ANTHONY F. CRAMER AND CHARLES J. DIEDERICH, OF DETROIT, MICHIGAN.

HEAT-INTERCHANGING APPARATUS.

No. 904,181.

Specification of Letters Patent.

Patented Nov. 17, 1908.

Application filed February 27, 1906. Serial No. 303,159.

To all whom it may concern:

Be it known that we, ANTHONY F. CRAMER and CHARLES J. DIEDERICH, citizens of the United States, residing at Detroit, in the 5 county of Wayne and State of Michigan, have invented a new and useful Improvement in Heat-Interchanging Apparatus, of which the following is a specification.

Our invention relates to an improvement 10 in heat-interchanging apparatus of the class employed for condensers, brine-coolers, heaters, and the like.

We have more especially devised our improvement, however, as an improvement in 15 the class of multiple-pipe condensers adapted to be used as the refrigerating agent in ice or refrigerating machines; and for that reason the following description is confined to the device as a condenser in the aforesaid 20 class. These condensers as hitherto provided, comprise a coil formed of double-pipes, consisting of an inner pipe for conveying the water to be used for cooling the gas conveyed through a surrounding outer 25 pipe, the gas being caused to travel in the opposite direction to that of the water. These so-called double-pipe condensers necessitate the use of stuffing-boxes for making 30 gas-tight connections between the pipes. The stuffing-boxes, under the severe strain to 35 which they are subjected by the unequal expansion and contraction of the pipes, frequently crack and break, thus impairing the condenser and rendering it necessary to empty it for making repairs.

Our primary object is to provide a condenser which shall enable stuffing-boxes to be wholly dispensed with; and this we accomplish by providing the triple-pipe construction of condenser hereinafter described, and illustrated in the accompanying drawings, in which—

Figure 1 is a broken view in side elevation of our improved condenser; Fig. 2, an enlarged broken view in vertical sectional elevation of a portion of the condenser; Fig. 3, a section taken at the line 3 on Fig. 2 and viewed in the direction of the arrow; Fig. 4, an enlarged broken view in end elevation of 45 the gas-inlet end of the condenser; Fig. 5, an enlarged broken view in sectional elevation at the gas-inlet end, taken at the line 5 on Fig. 4 and viewed in the direction of the arrow; and Fig. 6, a section taken at the line 50 6 on Fig. 5 and viewed in the direction of the arrow.

The condenser comprises a series of groups of triple concentric pipes A, each group of the pipes being composed of an inner pipe B, an outer pipe C, and an intermediate pipe 60 D. Each of the pipes C has secured upon one of its ends a male coupling ring C¹ and upon its opposite end a similar ring C².

E, E are return-bend couplings each provided with annular flanges E¹, E¹ at its 65 ends and with vertical flanged extensions E², E², the latter forming seats at which the return-bends are secured together in vertical series, as by bolts e, the lowermost extension being bolted to a standard e¹. The return-bends E connect the outer pipes C at one end of the coil, in pairs, beginning with the second group A from the top, the return-bends being secured to the pipes C, as by bolts e 70 passing through the flanges E¹ and the adjacent rings C¹ on the outer pipes.

The outer pipe C of the uppermost group is provided at its gas-inlet end with an elbow C³, instead of a return-bend, forming an inlet C⁴ for the compressed gas to be 80 condensed, the elbow being secured at its flanged portion C⁵ to the adjacent ring C¹ on the outer pipe.

F, F are return-bend couplings for connecting the ends of the outer pipes at the 85 opposite end of the coil, each being provided with lateral flanges F¹, F¹ and with flanged vertical extensions F², the latter forming seats at which these return-bends are secured together to support the coil. Each 90 return-bend F is also provided at its ends with tubular lateral extensions F³, F³, each of an internal diameter greater than the outside diameter of the intermediate pipe through and beyond which extension the 95 ends of the intermediate and inner pipes protrude, the return-bends F being secured to each pair of outer pipes in staggered relation to the return-bends E, on their opposite ends, as by bolts f¹ passing through the 100 flanges F¹ and adjacent rings C². The intermediate pipes D are threaded at their protruding ends and are fastened by rings G engaging with the flanges F³.

H, H are return-bends for connecting each 105 inner pipe B with the intermediate pipe D of the next upper group, and each is provided at its upper end with a tubular head H¹ of an internal diameter greater than the external diameter of the inner pipe which 110 extends through and beyond it. Each return-bend H is secured at its tubular head

H¹, as by bolts *g*, to the ring *G* on the intermediate pipe of which the return-bend forms an extension, and each return-bend *H* is provided with a threaded lower end *H*² into which the inner pipe, extending through the tubular head *H*¹ of the next lower group of pipes, is screwed. The lowermost outer pipe *C* is provided at its gas-outlet end with an elbow *C*⁶ between the rings *C*² and *G* on the lowermost outer and intermediate pipes, respectively, and terminates in a gas or liquid outlet *C*⁹, the elbow being of an internal diameter greater than the outer diameter of the intermediate pipe, and provided with a tubular extension *C*⁷ through and beyond which the intermediate and inner pipes of that group protrude. The elbow *C*⁶ is also provided with vertical flanged extensions *C*⁸, the uppermost one of which forms a seat for the lowermost extension *F*² on the lowermost bend *F*, and the lowermost one of which seats upon a standard *f*.

K is a tubular head beyond the ring *G* on the lowermost intermediate pipe, of an internal diameter greater than the external diameter of the inner pipe which extends through it, the head *K* being closed at its outer end by a cap *L* screwed on the end of the inner pipe and fastened, as by bolts *g*¹, to a flange *h* on the head. The head *K* is provided with an inlet-opening *K*¹ adapted to be connected to any suitable source of water supply, not shown, for supplying water through the head *K* and intermediate and inner pipes as will hereinafter be described. The uppermost inner pipe *B* is provided at its water-outlet end, beyond the tubular extension *H*¹ surrounding it, with a water-outlet pipe *M* screwed onto its projecting end.

Each of the intermediate pipes at the gas-inlet end of the coil is closed by a plug *i* and is sustained to render it free for longitudinal contraction and expansion independently of the outer pipe, on inwardly extending lugs *c*¹ on the outer pipes. Each of the inner pipes at its end adjacent to the plugged end of the surrounding intermediate pipe reaches short of the plug *i* and is sustained therein by lugs *d* on the intermediate pipe, adapting the inner pipe to contract and expand longitudinally independently of the intermediate pipe.

The operation of the condenser is as follows: Gas is admitted through the inlet *C*⁴ whence it passes between the outer and intermediate pipes of the upper group of pipes *A* to the uppermost return-bend *F*. Thence it passes in the opposite direction between the outer and intermediate pipes of the second group to the uppermost return-bend *E* and thence between the outer and intermediate pipes of the third group and through the outer pipes of the remaining groups until it reaches the gas-outlet *C*⁹, where it is dis-

charged in liquid condition owing to its subjection to cold water passing through the coil as will now be described.

The condensing water is admitted to the coil through the water-inlet *K*¹, whence it passes between the inner and intermediate pipes of the lowermost group to the plugged end of the intermediate pipe, thence into the open end of the surrounded inner pipe, and through it to the lowermost return-bend *H* at the water-inlet end of the coil, thence upward through the return-bend *H* through its tubular head *H*¹ and between the intermediate and inner pipes of the second lowermost group of pipes to the plugged end of the intermediate pipe, thence through the inner pipe of the same group, the water flowing as described through the intermediate and inner pipes of each surrounding group until finally discharged at the water-outlet *M*.

It will be seen that by providing in each pipe-group of the coil two concentric pipes for coursing the condensing water in contrary directions through each gas-conducting pipe, we are enabled to dispense entirely with the objectionable stuffing-boxes referred to, thus attaining an important advantage by our triple-pipe condenser over the type known as the double-pipe condenser. Moreover, our improvement enables each of the inner and intermediate pipes to be loosely supported at one of its ends, whereby they are free to contract and expand independently of each other, so that no damage can result to the connection from the rapid changes of temperature to which they are subjected in use.

What we claim as new and desire to secure by Letters Patent is—

1. A heat interchanging apparatus comprising a coil composed of a series of pipe-groups, each group consisting of an inner pipe, an outer pipe and an intermediate pipe, each intermediate pipe being closed by a plug at one end and communicating therewith the adjacent end of the inner pipe of the same group and connected at its opposite open end with the inner pipe of the next adjacent group, return-bends at one end of the coil beyond the plugged ends of the intermediate pipes, connecting the outer pipes at one end of the coil, and return-bends at the opposite end of the coil, through and beyond which the intermediate and inner pipes extend, for connecting the outer pipes at their opposite ends whereby a continuous passage through the outer pipes is provided, for the purpose set forth.

2. A heat interchanging apparatus comprising a coil provided with gas and water inlets and outlets and composed of a series of pipe-groups, each group consisting of an outer pipe, an inner pipe and an intermediate pipe, each intermediate pipe being

closed at one end and communicating thereat with the adjacent end of the inner pipe of the same group, return-bends beyond the closed ends of the intermediate pipes connecting the outer pipes at one end of the coil, return-bends at the opposite end of the coil for connecting the other ends of the outer pipes and through which return-bends the intermediate and inner pipes extend, and return-bends beyond said outer-pipe return-bends connecting the intermediate pipe of one group with the inner pipe of the next adjacent group throughout the series, for the purpose set forth.

3. A heat interchanging apparatus comprising a coil composed of a series of pipe-groups, each consisting of an outer pipe, an inner pipe, and an intermediate pipe, a gas-inlet at one end of the uppermost outer pipe, a water-outlet at one end of the inner pipe of the same group, a gas-outlet at one end of the lowermost outer pipes, and a water-inlet at one end of the lowermost intermediate pipe adjacent to the gas-outlet, each outer pipe being provided with rings on its opposite ends, each intermediate pipe being closed at one end and communicating thereat with the adjacent end of the inner pipe of

the same group, flanged return-bends beyond the closed ends of the intermediate pipes each secured at its flanged portions to the adjacent rings on the outer pipes for connecting them at one end of the coil, flanged return-bends at the opposite end of the coil each secured at its flanged portions to the adjacent rings on the outer pipes for connecting them at their opposite ends, and through and beyond which last-named bends the intermediate and inner pipes extend, rings on the open ends of the intermediate pipes, flanged return-bends each secured at one of its ends to the adjacent ring on the intermediate pipe and at its opposite end to the inner pipe of the next adjacent group of pipes for connecting the inner and intermediate pipes throughout the series, said intermediate and inner pipes being freely supported at their adjacent ends to permit longitudinal and independent expansion and contraction of the pipes, for the purpose set forth.
